(57) **CLAIM**

The ornamental design for a swim fin, as shown and described.

DESCRIPTION

FIG. 1 is a front, right and bottom perspective view of a swim fin, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is a front plan view with the claimed design shown in a paired environment.

The broken lines depict portions of the swim fin that form no part of the claimed design.

The showing of the broken line swim fin in FIG. 10 are included for the purpose of illustrating environmental structure and forms no part of the claimed design.

1 Claim, 10 Drawing Sheets
